BENJAMIN P. BAKER, OF TURTLE CREEK, AND ROBERT C. DICKINSON, OF WILKINSBURG, PENNSYLVANIA, ASSIGNORS TO WESTINGHOUSE ELECTRIC AND MANUFACTURING COMPANY, A CORPORATION OF PENNSYLVANIA

CIRCUIT BREAKER

Application filed September 11, 1929. Serial No. 391,734.

Our invention relates to circuit interrupters and particularly to circuit interrupters of the air-break type which embody deionizing chambers and blow-out magnets.

5 One object of our invention is to provide a circuit interrupter having an arcing chamber of the above mentioned type with a blow-out magnet which carries current only while the arc established upon the opening of the 10 circuit interrupter is being extinguished.

Another object of our invention is to provide means for forcing the current through the circuit interrupter to energize the windings of the aforesaid blow-out magnet.

15 It is another object of our invention to provide a blow-out magnet winding comprising a number of separate sections in series, and to so systematically arrange these sections as to minimize potential gradients to ground 20 and the amount of insulation required for the various structural elements of the deionizing chambers.

A further object of our invention is to provide means for causing the arcs established 25 in the deionizing chamber to move radially inward toward the centers of the plates composing the deionizing arrangement.

The arrangement used for inserting the blow-in winding in the circuit is advantageous over the use of separate transfer contacts for connecting the winding in the circuit, since the mechanical operating mechanism is simplified and the additional contacts are eliminated. This structure is an improvement over placing the winding in the shunt circuit so that it is energized by the opening of the main contacts, since, with such a structure, there will be an arc at the main contacts when they are opened due to the insertion of 30 the winding in the circuit, unless intermediate auxiliary contacts are provided on the main contacts. The structure of our invention is also desirable in that the only arc drawn is within the deionizing chamber 35 where it may be most effectively extinguished.

Decreased over-all operating time of the circuit breaker is also obtained with this structure, since there is no time delay before the drawing of the main arc to permit the operation of auxiliary main contacts or separate 50 transfer contacts.

Our invention will best be understood by referring to the following specification, taken in connection with the drawings, wherein

Figure 1 is a view, partly in section and 55 partly in elevation, of a deionizing chamber embodying our invention.

Fig. 2 is a detail view in elevation, of one of the metallic plates employed in the arc-deionizing chamber disclosed in Fig. 1. 60

Fig. 3 is a view in elevation of a pair of contacts of the general type shown in Fig. 1, but embodying a particular modification of our invention.

Fig. 4 is a view, similar to Fig. 1, of another 65 embodiment of our invention; and

Fig. 5 is a view partly in section of an upper portion of the deionizing chamber shown in Figs. 1 and 4.

Referring particularly to Fig. 1, the circuit interrupter embodying our invention comprises, in general, an arc extinguishing chamber 1 which encloses separable contacts 2 and 3. Above the contacts 2 and 3 are positioned deionizing plates 4. The arc incident 70 to the opening of the contacts 2, 3 under load is moved upward into the spaces between the plates 4 and is rotated about a recurrent path therein until it is extinguished when the current passes through the zero value during the 75 course of its alternating cycle. Such a deionizing structure has been described and claimed in the co-pending application of J. Slepian, Serial No. 181,289, filed April 6, 1927, and that of Benjamin P. Baker, Serial 80 No. 187,987, filed April 30, 1927, and assigned to the Westinghouse Electric & Manufacturing Company, the assignee of the present application. 85

Adjacent the ends of the series of plates 4 90

are positioned arc forms comprising a set of plates 5 having ventilating spaces therebetween providing a means of exit for the air and gases that would otherwise be trapped ahead of the arc rotating within the chamber 5. Such a structure is described in the co-pending application of Robert C. Dickinson, Serial No. 317,617, filed November 6, 1928, and assigned to the assignee of the present 10 application.

A series of deionizing metal plates 6 is provided below one of the above-mentioned sets of arc horn plates 5, the plates 6 being insulated from each other and from the plates 15 5 and from the line conducting member 7 which supports the stationary contact member 2. A winding 8 which surrounds the path of the arc provides a magnetic field for forcing the arc drawn between contacts 2 and 20 3 into the deionizing plates 4. It will be evident upon examination that the winding 8 is normally not traversed by the current flowing through the contacts 2 and 3, but that it is energized immediately after the separation 25 thereof. It will be seen that the current is forced to flow through the winding 8, as just described, by reason of the fact that the terminals 9 and 11 of the winding 8 are connected, respectively, to the arc horn plates 5 30 and the conductor 7 and hence the winding 8 is made to shunt the insulated metal plates 6.

The operation of the above-described arrangement is as follows. The arc, which is drawn when the movable contact member 3 is 35 separated from the stationary contact 2, impinges on an extension 12 of the arc horn plates 5 and is immediately divided into two sections, as indicated by reference numerals 13 and 14. The extension 12, or the arc horn 40 plates 5, themselves, may, if desired, be made of a magnetic material. As the movable contact member 3 completes its movement away from the venting plates 5, the terminus of the arc is transferred from member 3 to the 45 plates 5 and the portion 14 of the arc will thereupon assume the position indicated at 15 in Fig. 1.

At the same time, the arc 13 has been transferred to the plates 6 and is thus in parallel 50 with the winding 8. The line current at once begins to flow through the winding 8. The arc 13 and the winding 8 are then in parallel and each must have the same voltage drop thereacross. If the voltage drop in the winding 55 is less than the high voltage required to maintain the arc when split up into short arcs between the deionizing plates 6, the arcs will be extinguished and the entire current will flow through the winding 8 for providing the blow-in field. The length of time that will 60 be required for the entire current to transfer from the arcs between plates 6 to winding 8 will depend on the inductance of the latter and the magnitude of the current. It will 65 be seen that the voltage effective for trans-

ferring current to the winding 8 is substantially the voltage drop across the series of arcs between plates 6. In order that this voltage drop shall be sufficiently great a plurality of plates are employed to make up the section 6. Noting that it is the magnetic field set up by winding 8 which forces the arc section 15 to move into the spaces between deionizing plates 4, it will be seen that the higher the transfer voltage, the quicker the aforesaid field will be set up and the sooner the main arc 15 will be driven into the deionizing chamber and extinguished. 70 75

For the foregoing reason, it will be seen that the arc 13 should move only a short distance before it is broken up into a series of short arcs, thus greatly increasing the voltage necessary to maintain the arcs. 80

As previously stated, the main arc 15 is forced into the slot or channel 16 formed, as indicated in Fig. 2, in the lower end of plates 4. By the time the arc has reached the apex of the slot 16 in the plates 4, which is the time that the greatest amount of driving force is required, the magnetic field induced by winding 8 has been built up to a sufficient strength to exert the required force on it. 85 90

While the above-described arrangement has proved satisfactory for most conditions of service, a modification thereof, shown in Fig. 3, may be found desirable in certain instances. Referring to the latter figure, a contact 34 is pivoted on the venting plates 5 and is biased into contact engagement with the movable contact member 3. 95 100

When the contacts 2 and 3 first separate, an arc is drawn in parallel relation with the winding 8 due to the whole voltage drop across the winding being impressed across the small space between contacts 2 and 3 at the instant of contact separation. In consequence current rises rapidly in value in the latter and a considerable magnetic field is quickly built up. The main arc is drawn shortly afterward between the contacts 3 and 34, and thus the latter is immediately acted on by a substantial blow-out field and moved into contact with the deionizing plates 4. 105 110 115

A structure similar to that just described in connection with Fig. 1, is shown in Fig. 4, with the exception of the fact that a central portion of the series of deionizing plates 4 serves the same purpose as the separate series of plates 6 of Fig. 1. Considerable advantage is inherent in this structure, as will now be pointed out. 115 120 125

In Fig. 4 the contacts 17 and 18 are both of the movable type and are positioned adjacent a central section 19 of the deionizing plates. The outer plates 21 and 22 of the section 19 extend almost to the movable contacts 17 and 18 and are bent backwardly upon themselves, thus forming U-shaped members. The plates 23, located between the outer plates 21 and 130

22, are of greater length than the deionizing plates 4 and extend downwardly to a position adjacent the central portion of the arc path. Iron members 24 and 25 may, if desired, be positioned at the bottom of the U-shaped plates 21 and 22, to strengthen the field at that point in order to effect a quick transfer of the arc from contacts 17 and 18 to plates 21 and 22. In circuit with the upper ends of the plates 21 and 22 are conductors 26 and 27 which overlap each other in the middle of the deionizing structure. The plates 21 and 22 are insulated from the deionizing plates 4.

When the contacts 17 and 18 are separated, an arc is drawn and moves upwardly because of the magnetic effect of current in the arc and contacts. As a result the arc immediately impinges on the ends of the plates 21 and 22 and is broken up into a plurality of arc sections designated by numerals 29, 31 and 32.

The flow of current through U-shaped members 21 and 22 sets up a magnetic field which acts upon the central arc 31 and the two-main arcs 29 and 32, thus forcing them upwardly while the blow-out field is being built up. A somewhat similar utilization of the blow-out effect of current flow in U-shaped plates is disclosed in the co-pending application of J. Slepian, Serial No. 331,469, filed January 10, 1929, and as signed to the assignee of the present application.

As soon as the arc 31 is established, the line current begins to flow through the conductors 26 and 27 to the winding 8, thus quickly placing the latter in series with the portions of the arc designated by numerals 29 and 32.

It will be noted that the direction of flow of current in the conductors 26 and 27 will be such that it is parallel to and in the same direction with the flow of current through the arcs between the upper portion of the plates 4.

In addition to the magnetic field set up by windings 8, the radial field is induced by a plurality of coils 33 which are positioned at intervals among the plates 4. Such an arrangement for inducing a radial field is described in the above-mentioned application of Benjamin F. Baker.

The parallel paths of current in the conductors 26 and 27 and the arcs between plates 4 causes the latter to move toward the said conductors and hence into a stronger portion of the radial field provided by the coils 33. By thus utilizing the central portion of the radial field, its effectiveness in moving the arcs over the surfaces of the deionizing plates 4 is raised to a maximum.

An advantage additional to that just described is inherent in the centrally located arc structure just described for forcing current flow in the winding 8. In general, the line voltage is distributed in a potential

gradient among the series-connected deionizing plates and magnetizing coils; but as between the blow-in coils and plates this gradient is not uniform, since all portions of the coil are at substantially the same potential. 70

Where a dissymmetrical arrangement is employed, such as that in Fig. 1 where the winding 8 is electrically connected at one end of the aggregate structure and is at the potential of the line connected to that end, 75 the gradient may be concentrated near one end of the structure by reason of the difference in capacitance to ground of coils and plates. This difficulty may be corrected by providing an additional layer of tinfoil to 80 cover a suitable portion of the enclosing wall of the deionizing chamber. But by reason of the symmetry of the Fig. 4 arrangement of coils and plates concentration of voltage gradient at one end of the structure is avoided, 85 since the coil is at the potential of the center plates in the stack, rather than at the potential of either of the line terminals; and the foil layer just alluded to is not required. Fig. 5 shows at 41, 42, 43 layers of foil properly disposed to produce a uniform potential 90 gradient in the structure shown in Fig. 4.

The elimination of the layer of metal foil was found in a practical case to reduce the insulation required between the edges of 95 plates 4 and ground by one-third.

Such being the nature of various structures embodying our inventions, the foregoing facts may be summarized by saying that we have provided a simple and effective means 100 for transferring the current of an arc to a blow-out magnet winding; that our structure most effectively utilizes a radial magnetic field in causing rotation of an arc in a deionizing chamber; and that we have disclosed 105 an arrangement adapted to minimize electrostatic unbalance in a structure comprising a series of deionizing plates and blow-out coils and thereby to minimize the amount of insulating material required to be employed. 110

While we have described a particular embodiment of our invention, it is to be understood that many changes, additions, omissions and substitutions may be made therein without departing from the spirit and scope 115 of our invention. Therefore, we do not wish the appended claims to be limited except in the respect made necessary by the prior art.

We claim as our invention:

1. Circuit-interrupting means comprising 120 means for establishing an arc, an arc-extinguishing device associated therewith, a normally deenergized winding associated with the said device, means including a portion of said arc for inserting said winding 125 in circuit with another portion of said arc, and magnetic means for initially moving the arc until said winding is energized.

2. Circuit-interrupting means comprising 130 means for establishing an arc, an arc-ex-

tinguishing device associated therewith, a normally deenergized winding associated with said device, means adapted to subdivide said arc longitudinally, one portion of said arc acting to insert said winding in circuit with another portion of said arc, and conducting means energized by the arc current for initially moving the first said portion of the arc during the time the current thereof is being transferred to said winding.

3. Circuit-interrupting means comprising means for establishing an arc, an arc-extinguishing device associated therewith, a winding for moving the arc and means for dividing the arc into a plurality of sections, one of said sections being initially divided into a plurality of arcs in shunt with said winding.

4. Circuit-interrupting means comprising means for establishing an arc, an arc-extinguishing device associated therewith, means of magnetic material providing a magnetic circuit associated with said device, a winding for energizing said magnetic circuit and means for dividing the arc into a plurality of sections, one or more of which shunts said winding, means for rapidly moving that portion of said arc that shunts said winding and means for dividing the last said arc portion into a plurality of arcs.

5. The combination with a circuit interrupter having separable contact members, of an arc-extinguishing means associated therewith, a magnetizing winding associated with the said means, means adjacent said contacts for dividing an arc between said contacts into a plurality of sections, and means for initially moving said arc until said magnetizing winding is energized, said means comprising an arc terminal member in which the arc current flows.

6. The combination with a circuit interrupter having separable contact members, of an arc-extinguishing means associated therewith, means of magnetic material providing a magnetic circuit associated with said means, an electrical circuit for energizing said magnetic circuit and means associated with said contacts for dividing an arc established thereby into a plurality of sections, one of which sections shunts said winding, and means for initially moving the arc under the action of a magnetic field until said winding is energized.

7. The combination with a circuit interrupter having separable contact members, of an arc-extinguishing means associated therewith, a winding for causing a magnetic field about said means, means associated with said contacts for dividing an arc established thereby into a plurality of sections, the first of said sections which is established being in parallel with said winding, and means for initially moving said arcs before said winding is completely energized.

8. The combination with a deionizing chamber wherein a radial magnetic field is

provided to move a plurality of arcs on spaced conducting plates, of a conductor in series with the said arc and passing centrally through the said field and connected at its ends to a pair of said plates adjacent the center of said plurality of plates in such a manner that the currents flowing through said conductor and said arcs are in the same direction.

9. The combination with a deionizing chamber wherein a radial magnetic field is provided to move a plurality of arcs among a stack of spaced conducting plates, of contacts associated with said chamber for drawing an arc, a winding for moving the arc into said chamber, and means including a portion of said winding forming a parallel path with said arc for retaining the arc centrally on the said plates, said winding having its ends connected to a pair of said plates at the central portion of said stack.

10. The combination with a wound coil providing a radial magnetic field for rotating an arc within a stack of spaced conducting plates, a conductor passing through said coil and plates and forming a parallel path with said arc.

11. In combination with a plurality of windings providing a radial magnetic field to move a plurality of arcs between spaced conducting plates, said windings having their ends connected between spaced pairs of said plates, a conductor passing through the windings in a manner such as to form a current path parallel with said arcs and in which the current flows in the same direction as in said arcs.

12. In combination with a plurality of windings providing a radial magnetic field to move a plurality of arcs between spaced conducting plates, a conductor in series relation with said arcs and associated with said magnetic field and said windings in such a manner so as to cause said arcs to traverse a path which is central in said field, said conductor having its ends connected to a spaced pair of said plates.

13. In a circuit interrupter, a pair of separable contacts, a pair of arc terminal members, one of said contacts, when in its closed position, being disposed closely adjacent one of said terminal members, but slightly spaced therefrom and at a distance from the other of said terminal members, and a magnetizing circuit connected between said contact member and terminal member which are disposed adjacent each other when the contacts are closed, and the other of said contacts being movable to transfer the end of the arc drawn thereon to said other terminal member.

14. In a circuit interrupter, means for extinguishing an arc comprising a plurality of spaced plates for splitting up the arc into a plurality of short arcs, a pair of separable contacts for drawing the arc outside of said

- plates, a pair of arc terminal members, one of said contacts, when in its closed position, being disposed closely adjacent one of said terminal members but slightly spaced therefrom and at a distance from the other of said terminal members to which one end of the arc is transferred, and a magnetizing circuit connected between said contact member and terminal member which are disposed adjacent each other when the contacts are closed, said magnetizing circuit being arranged to move said arc between said pair of arc terminal members into said plates to be extinguished.
15. In a circuit interrupter, means for drawing an arc, means for extinguishing said arc comprising a plurality of spaced metal plates, two of said plates having a portion which splits up the arc extending beyond the corresponding portion of other of said plates, and a conducting winding having its ends connected to said plates which have their extended portion.
20. In a circuit interrupter, means for extinguishing an arc comprising a plurality of conducting members for splitting the arc into a plurality of arcs, means for initially drawing the arc in a path spaced from said extinguishing means, means for moving said arc into said extinguishing means comprising a magnetizing coil having its ends connected to a pair of said conducting members extending beyond other of said members to a point near the path where the arc is initially drawn.
25. In a circuit interrupter, means for extinguishing an arc comprising a plurality of spaced conducting plates for separating the arc into a series of short arcs, means for initially drawing the arc at a point spaced from said extinguishing means, means for setting up a magnetic field for moving said arc into said plurality of plates comprising a conducting loop having its ends connected to a pair of stationary arc terminal members extending to a point near the path where the arc is initially drawn.
30. In a circuit interrupter, means for extinguishing an arc comprising a plurality of spaced plates for splitting up the arc into a plurality of short arcs, said plates having holes therein, means for drawing the arc outside of said plates, means for moving the arc into said plates comprising a conducting loop extending through the holes in said plates and so connected to a spaced pair of said plates that the arc current flows in the portion of the loop through said holes in the same direction as the current in the arc.
35. In a circuit interrupter, means for drawing the arc, and a magnetizing loop having its ends connected to one side of each of said U-shaped plates.
40. In a circuit interrupter, means for drawing an arc, means for extinguishing said arc comprising a plurality of spaced metal plates, two of said plates being of U-shape with the bottom of the U extending beyond the other of said plates at a point near that portion of the arc which is first drawn, and a magnetizing loop having its ends connected to one side of each of said U-shaped plates.
45. In a circuit interrupter, means for drawing an arc, means for splitting up said arc into a plurality of sections including arc terminal members on which the ends of said arc sections play, means for later splitting up each of said arc sections into a plurality of short arcs, and a magnetizing winding for moving the arc having its ends electrically connected to said arc terminal members.
50. In an arc-extinguishing structure, a plurality of plates of conducting material, means for splitting the arc into a plurality of sections between certain of said plates, and means connected between said arc sections for setting up a magnetic field for moving each of said arc sections, the other of said plates causing each of said arc sections to be split up into short arcs after the energization of said magnetic field means has moved said arc sections thereinto.
55. In testimony whereof, we have hereunto subscribed our names this 29th day of August, 1929.
